UNITED STATES PATENT OFFICE.

LEWIS E. LOCKLING, OF PERRYSBURG, AND NATHANIEL N. WHITAKER, OF SHERIDAN, NEW YORK.

IMPROVEMENT IN FENCES.

Specification forming part of Letters Patent No. **103,903**, dated June 7, 1870.

To all whom it may concern:

Be it known that we, LEWIS E. LOCKLING, of Perrysburg, in the county of Cattaraugus, and NATHANIEL N. WHITAKER, of Sheridan, in the county of Chautauqua and State of New York, have invented a new and useful Improvement in Fences; and we do declare that the following is a true and accurate description thereof, reference being had to the accompanying drawings, and to the letters of reference marked thereon, and being a part of this specification, in which—

Figure 1 is a perspective view of our combined wooden and wire fence. Fig. 2 is an elevation of one of the arched and looped standards thereof. Fig. 3 is a side elevation, showing our improved method of securing the ends of the top rails to each other when erected on hilly or broken ground. Fig. 4 is an end view of the same. Fig. 5 is a plan of our metallic socket for joining two or more rails at right angles, as in turning corners or in uniting a division-fence with the main line.

Similar letters of reference indicate corresponding parts in each figure.

The nature of this invention relates to an improved construction of fences composed partly of wood, but chiefly of iron wire, and is more especially designed as an improvement on the fence described in Letters Patent numbered 58,848, issued October 16, 1866, to Lewis E. Lockling.

It consists, first, in a novel and effective method of securing the ends of the top rails together in said loops to prevent them from being pulled apart in exposed situations; second, in a standard at the end of a section of fence, secured to the arched standard and top rail, to which the wires of the fence are secured, and which are prevented from swaying by passing through loops in a twisted wire suspended in the arch; and in the general arrangement of its parts, as hereinafter more fully shown and set forth.

In the drawings, A represents an arched standard, having in its upper part a loop, B, formed by twisting half around the rod from which the standard is made. The lower ends are secured in any suitable foundation, or driven into the earth, forming a post to sustain the

fence. The loops B receive the ends of the top rails, C, which may be inserted therein side by side, or "halved" in, as most convenient; but on hillsides or broken ground, where they would draw away from each other, they are locked together, as shown in Figs. 3 and 4. The locking is effected by making a tenon, a, on the ends of the rails, with a groove in the tenon adjoining its outer shoulder, in which the loop rests when the rails are in place, where they are secured by wedges b driven between them. To more effectually resist longitudinal strain on the rails, pins c may be driven through both rails at either side of the loop.

D is a standard, of wood or metal, in the form of an inverted T. Its shorter arms are secured to the base of the standard A, and its longer arm to the top rail, by wood-screws or otherwise. It is provided with two rows of holes disposed in pairs, through which the ends of wires E are passed and looped or twisted, to fasten them at the ends of the sections of fence.

F is a twisted wire, secured to the upper part of the arch in the standard A, extending downward, embracing in its course the horizontal wires E, and has its lower ends secured to the lower limbs of the standard, dividing the strain on the standard or brace D and preventing the wires E from swaying.

G is a clamp or socket, of cast or wrought metal, and is employed to join the ends of two upper rails together, at right angles with each other, by means of screws or bolts, in turning a corner, saving the time and expense of mortising the rails together. Where a division-fence is to be joined to the main line, two of the clamps are used, in connection with a plate, G', as shown in Fig. 5.

In place of the wires E bars or rails of wood may be employed in connection with the standards A, constructed as above described, and top rails, C; but such use of wooden bars forms no part of the present invention.

On very steep hillsides the fence may be further strengthened by a tension-rod extending from the base of one standard to the top of the next one below.

What we claim as our invention, and desire to secure by Letters Patent, is—

1. The upper rails, C, provided with tenons

a and wedges *b*, in combination with the loops *B*, substantially as described, and for the purpose specified.

2. The standards *D*, of the form of an inverted **T**, at the end of a section of fence, secured to the arched standard *A* and top rail, *C*, in combination with the twisted wire *F* and the horizontal wires *E*, when constructed as described, and arranged to operate as and for the purpose set forth.

3. The arrangement of the standards *A* and *D*, the loop *B*, the rails *C*, provided with tenons *a* and wedges *b*, the wires *E* and *F*, and the clamp *G*, when constructed as described, and for the purpose set forth.

L. E. LOCKLING.
N. N. WHITAKER.
